UNITED STATES PATENT OFFICE.

JAMES E. MERWIN, OF SEATTLE, WASHINGTON.

CHAIN PUMP.

1,098,953.

Specification of Letters Patent.

Patented June 2, 1914.

Application filed April 28, 1913. Serial No. 764,204.

To all whom it may concern:

Be it known that I, JAMES E. MERWIN, a citizen of the United States of America, and a resident of the city of Seattle, in the county of King and State of Washington, have invented certain new and useful Improvements in Chain Pumps, of which the following is a specification.

My invention relates to chain pumps, the same having particular reference to that type wherein the water or other liquid is elevated through a pipe by a series of pistons, and has for one of its objects the provision of a simplified construction which is efficient in operation.

A further object resides in providing a novel means for locking the liquid elevating means against reverse movement when the latter has stopped, and which is adapted to be automatically moved to an inoperative position, when the pump is set in motion, by the elevated liquid.

With the above and other objects to be referred to as my description progresses, my invention resides in the features of construction, arrangements and combinations of parts hereinafter described and succinctly defined in my annexed claims.

Referring to the accompanying drawing wherein like numerals of reference indicate like parts throughout: Figure 1 is a side elevation of the present invention parts thereof being broken away for the sake of clearness. Fig. 2 is a top plan view thereof parts being broken away. Fig. 3 is a perspective view of one of the pistons employed in my invention, and Fig. 4 is a fragmentary side elevation of a slightly modified construction.

Referring more particularly to the drawing, 1 designates a frame on which the pump is supported. Depending from the top of the frame 1 is an up-take pipe 2 having the component parts thereof suitably secured, as by the bolts 3, and the lower terminal thereof flared outwardly to facilitate the reception of the pistons 4. These pistons, which conform to the contour of the pipe 2, are supported by a chain or cable 5 taking over a notched wheel 6 supported on the top of the frame 1 adjacent the upper terminal of the pipe 2 and over a second notched wheel 7 supported by said pipe adjacent to its lower terminal.

The shaft 8 which supports the wheel 6 carries on one terminal a ratchet wheel 9 and on its opposite terminal a gear 10, the latter

meshing with a second gear 11 which is driven by any suitable power. Each piston 4 has depending from its under side a pair of spaced arms or webs 12 which are adapted to bear against the inner wall of the pipe 2 when lifting water to prevent the piston from tipping. Friction wheels 13 are mounted on the lower end portions of the arms 12 to facilitate the operation of the pump.

Cooperating with the ratchet 9 is a pawl 14 which prevents a backward or reverse movement of the wheel 6. When the pump has been stopped the water in the pipe 2 supported by the pistons 4 would under ordinary circumstances cause a reverse movement of the chain were it not for the pawl 14.

After starting the pump and when the same is in motion, it has been found desirable to raise the pawl from engagement with the ratchet 9 and to accomplish this a certain novel construction is provided which is operated by the elevated liquid and which when the liquid ceases to flow will automatically return the pawl 14 into engagement with the ratchet 9. This construction consists of a lever 15 mounted on the frame 1 and adapted to engage beneath the pawl for raising the latter free from the ratchet 9. The lower terminal of the lever 15 is connected by a link 16 to an arm 17, the latter being rigidly secured on a shaft mounted for movement in a trough 18 communicating with the pipe 2 adjacent the upper terminal thereof. Within the trough 18 is mounted on this shaft a depressible plate 19 which is adapted to be depressed by the elevated liquid flowing through the trough 18. Stops 20 are secured to the sides of the trough 18 to limit the upward movement of the plate 19.

As will be seen in Fig. 1 the inner edges of pistons 4 are received within the notches of the wheel 6 to establish a driving connection between the latter and the chain.

In operation, the wheel 6 is driven by any source of power through the gears 10 and 11 whereby the chain 5 is caused to move in the direction of the arrow shown in Fig. 1. As the chain 5 moves upwardly through the up-take pipe 2, the liquid is thereby elevated to the trough 18 and as it passes over the plate 19, the latter is depressed, and through the several connections the lever 15 raises the pawl 14 from engagement with the ratchet 9. Upon stopping the pump and the water ceasing to flow, the weight of the link

16 and the arm 17 will reverse the lever 15 whereby the pawl 14 is brought into operative engagement with the ratchet 9.

In the modification shown in Fig. 4 a float 5 21 is provided to perform the function of the 10 depressible plate 19 described in Fig. 1, said float being carried by a shaft mounted in the sides of the trough 18 and on one protruding terminal of the shaft, is mounted an 15 arm 22 which is adapted to bear against the free terminal of the pawl 23, the latter engaging the ratchet 9. In the modified construction, the wheel 24, over which the chain 5 takes, is provided with teeth to establish 20 a driving connection between said chain and wheel.

Having thus described my invention, what I claim as new, and desire to secure by Letters Patent of the United States of America, 25 is:—

1. A pump comprising a pipe, a pump chain operating therein and spaced from the inner wall of the pipe, means for operating the chain, pistons carried by the chain, and 25 a positioning arm projecting from each of the pistons for engagement with the wall of the pipe.

2. A pump comprising a pipe having an 30 outlet, means for elevating a liquid in the pipe, a wheel for operating the liquid elevating means, means for preventing a reverse movement of said wheel, and means disposed in the outlet of the pipe and oper-

able by the out-flowing liquid for releasing the second mentioned means. 35

3. A pump comprising a pipe, liquid elevating means in the pipe, a wheel for operating said means, a shaft supporting the wheel, a ratchet on the shaft, a pawl co-operating with the ratchet to prevent a reverse movement of the wheel, and means operable by the elevated liquid to release the pawl from the ratchet. 40

4. A pump comprising a pipe, means for elevating a liquid therein, means to prevent 45 a reverse movement of the elevating means, and means operable by the elevated liquid for releasing the second mentioned means.

5. A pump comprising a pipe, a pump chain operating therein, a piston carried by 50 the chain, spaced arms on the piston receiving the chain therebetween, and adapted to bear on inner wall of the pipe.

6. A pump comprising a pipe, means for elevating a liquid therein, and means normally preventing reverse movement of the elevating means and operable by the elevated liquid to release the elevating means aforesaid. 55

Signed at Seattle, Washington, this 4th 60 day of April, 1913.

JAMES E. MERWIN.
